DRAFTING INSTRUMENT

Gregory S. Dolgorukov, Detroit, Mich.

Application April 9, 1943, Serial No. 482,432

9 Claims. (Cl. 33—174)

This invention relates to drafting instruments and more particularly to an improved lettering guide.

It is well appreciated in the art that a substantial part of the total time of making a drawing, particularly an engineering or working drawing, such as those prepared in large numbers in engineering departments of manufacturing concerns, is consumed by the task of making necessary notes on such drawings. It is required that such notes be done in a certain standard style of lettering, be neatly made and arranged. Making such notes is tedious work requiring much skill and attention. In order to facilitate lettering and to insure uniformity of letter sizes and neat arrangement of notes, guide lines are usually drawn on the paper to provide limit lines for the tops and bottoms of lettering characters. A considerable number of instruments has been developed to facilitate drawing of such guide lines.

Whatever may be the instrument or the method employed in drawing the guide lines, a large amount of time is consumed in drawing such lines. Moreover, after the notes have been lettered in, it is customary to erase as much of the guide lines as is practical in order to improve the appearance of the drawing. However, since erasing of the guide lines between the letters of a word is impractical, said lines are erased only between separate words and are left intact between the letters. Such half erased broken lines detract very much from the neatness of a drawing done in pencil. Since most engineering drafting is nowadays done in pencil, it may be stated that the necessity of first drawing and then partly erasing guide lines in notes is somewhat of a nuisance in engineering drafting, and that in many cases it takes as much as 10% to 15% of the entire time spent in preparation of a drawing.

In view of the above many attempts have been made to provide means whereby lettering on drawings could be done without the necessity of drawing guide lines. Many draftsmen letter notes by putting a sheet of cross section paper under the drawing. Such practice is limited, however, to the use of highly transparent drawing paper, and cannot be used for ordinary paper. Even in cases of semi-transparent paper or tracing cloth, the lines can be seen only faintly, and, since the draftsman has to watch the pencil point very closely in order not to overdraw the lines, a severe eyestrain is imposed on the draftsman. Moreover, lettering characters so produced are, in

fact, limited to only one size, namely, the size in which the paper is graduated, since doubling or tripling the size provided on the cross sectional paper does not produce the different proportional sizes of the characters required in a note, i. e., proper sizes of figures, capitals, fractions, and the like, for a certain nominal size of line letters.

To avoid the above difficulty lettering guides or stencils of the "individual letter" type are often used, which stencils give the outline of each individual character, line letters and capitals, as well as each figure for a definite size of line letters. There are also lettering devices of the same "individual letter" type in which a two-stylus writing instrument is used, one stylus following grooves in the shape of each individual letter on a templet, while the other stylus reproduces the corresponding outline on the drawing. All "individual letter" guides, while very advantageous in use for large letters such as are used on title blocks or small signs and posters, particularly for ink work, are practically prohibitive in required time for regular engineering lettering where it is necessary to write in pencil long notes in small letters, $\frac{1}{16}$ " to $\frac{1}{8}$ " in height.

Attempts have been made to letter through a narrow slot cut in some existing drafting instrument, such as a triangle. Such lettering possesses many advantages and solves many difficulties connected with the use of guide lines as well as with the use of "individual letter" guides and stencils. However, the devices for lettering through a slot, developed so far, proved to have a number of serious disadvantages preventing their acceptance for wide use. One of the most serious disadvantages of these instruments is found in the difficulties connected with their use in the average run of engineering lettering where a word may be followed by a fraction extending higher and lower than the tops and the bottoms of line letters, or a figure which is usually higher than line letters; again, some words may begin with capitals. Moreover, several sizes of letters are usually necessary for a drawing in order to give some portions of notes more prominence or to provide more distinctive titles and title blocks. Using the slot only for some small portions of notes is very tiresome and annoying. On the other hand, providing a number of slots of different widths along various sides of a drafting instrument such as a triangle, or one slot above the other in a ruler or similar instrument, requires turning the device with every change in the height of the letters, or moving it in such a way as to require new setting of the slot against

the line of letters. Such operations make lettering through these slots rather difficult.

One of the objects of the present invention is to provide an improved drafting instrument with the aid of which it is possible to write accurately, rapidly and neatly large amounts of small letter notes on drawings, thereby saving much time and effort in the work of drafting.

Another object of the invention is to provide an improved drafting instrument, and particularly an instrument with the aid of which small letter notes may be neatly written without the necessity of first drawing guide lines therefor.

A still further object of the invention is to provide an improved drafting instrument for use particularly, but not exclusively, in engineering drafting, whereby a great saving of both time and money in the preparation of engineering drawings may be effected.

A still further object of the invention is to provide an improved lettering instrument, the use of which makes lettering much simpler and easier, whereby the time for training draftsmen is considerably shortened, and the drafting work is made more pleasant.

A still further object of the present invention is to provide a lettering guide or device for lettering through a slot giving uniform and predetermined height of letters, and which also enables rapid alternate lettering in characters of various heights, such as when beginning some words with capitals, writing figures and fractions immediately after or before line letters, and the like.

A still further object of the present invention is to provide an improved lettering device of the character specified in the preceding paragraph which permits lettering a line of mixed characters of various heights without turning the device or without resetting it by moving transversely of the letter line.

A still further object of the present invention is to provide an improved lettering guide which enables neat and speedy lettering of relatively long notes on engineering drawings, the separate lines of said notes containing lettering characters of various heights, such as line letters, capitals, fractions, and the like, each of the characters being of a predetermined height and arranged in a predetermined axial or transverse relationship to other characters of the same line.

A still further object of the present invention is to provide an improved lettering guide of the character specified in the preceding paragraph, which enables the production of neat and relatively long lines of lettering characters of predetermined varying but even heights, the same being done without imposing an undue strain on the draftsman's eyes, which as is appreciated in the art, is a very serious problem in the art due to the necessity of straining one's eyes in lettering between two faintly drawn guide lines or watching lines on the cross sectional paper through drafting paper or cloth of low transparency.

It is an added object of the present invention to provide a structure of the foregoing character, which is simple in construction, dependable in operation, and relatively inexpensive to manufacture.

Other objects of this invention will appear in the following description and appended claims, reference being had to the accompanying drawing forming a part of this specification, wherein like reference characters designate corresponding parts in the several views.

Fig. 1 is a view illustrating my improved lettering guide arranged in an operative position on a drawing against the guiding edge of a T-square.

Fig. 2 is a view showing the effective portion of the lettering guide on an enlarged scale.

Fig. 3 is a sectional view taken in the direction of the arrows on the section plane passing through the line 3-3 of Fig. 2.

Fig. 4 is a view showing the outline of the slots, the width of the slots being somewhat exaggerated for the sake of clarity, said view illustrating the use of the guide for writing figures, fractions and inch signs.

Fig. 5 is a view similar in part to Fig. 4 and illustrating the use of the guide for lettering title block letters.

Fig. 6 is a view similar in part to Figs. 4 and 5 and illustrating the use of the guide for writing in lower case letters.

Fig. 7 is a view showing a modified outline of the slots enabling a more convenient writing of title block letters in vertical stroke.

Before explaining in detail the present invention it is to be understood that the invention is not limited in its application to the details of construction and arrangement of parts illustrated in the accompanying drawing, since the invention is capable of other embodiments and of being practiced or carried out in various ways. Also it is to be understood the phraseology of terminology employed herein is for the purpose of description and not of limitation, and it is not intended to limit the invention claimed herein beyond the requirements of the prior art.

It should be noted, that the term "line letter" as herein used designates a small letter intended to follow a capital of a given size, such as the letters, o, m, p, a, n, and y following capital C in Fig. 4.

Use of the term "lower case letter" in the same sense has been avoided. In the art the term "lower case letters" designates smaller letters which are not only smaller in size but in most cases have different outlines than their respective capitals. (See Fig. 6.) This term, proper in use in the art of printing, may be misleading herein, since in the art of engineering drafting lower case letters are nowadays very seldom used and are, with the exception of rare instances, substituted by smaller letters having the same outline as their respective capitals (see Fig. 4).

Referring to the drawing, the lettering guide illustrated therein comprises a body 10, made preferably in the form of a flat rectangular strip of substantially transparent material, such as cellulose nitrate or cellulose acetate, commercially known as "Celluloid," said body being provided with a straight guiding edge 11. Parallel to said edge 11 there is provided a plurality, in the present instance three, of slots 12, 14 and 15. The right-hand end of the wide slot 12 merges into the left-hand end of the intermediate slot 14, while the right-hand end of the intermediate slot 14 merges into the left-hand end of the narrow slot 15. By virtue of such a construction there is provided, in effect, on the body 10 a single combination slot comprising the above mentioned mutually merging or communicating slot portions 12, 14 and 15 which extend parallel to the guiding edge 11.

The slots 12, 14 and 15 have their respective widths and axial arrangements selected in a predetermined relationship to each other in order to provide for lettering of all characters of at least one "font" of lettering characters, which is to say one complete assortment of characters

of one style and mutually related sizes, which one may need for use in notes on engineering drawings or charts for which lettering guides are employed. For general industrial purposes the arrangement of slots herein illustrated and described has been found to be very efficient. I prefer to make the narrow slot of such a width as to produce line letters $\frac{1}{8}$ inch high, although slightly smaller or larger line letters may be required for special purposes. It should be noted that the actual width of a slot has to be slightly (approximately $\frac{1}{4}$ inch) larger than the desired height of the letter characters to be lettered therethrough in order to allow for the clearance occurring between the edge of the slot and the pencil point.

The width of the narrow slot is in the nature of a basic dimension from which the respective widths of the other slots are derived. The width of the intermediate slot is approximately one and a half times that of the narrow slot, while the width of the wide slot is slightly over twice the width of the narrow slot. By such an arrangement the intermediate slot becomes suitable, as far as its width is concerned, for lettering therethrough capitals and figures for the whole numbers, while the wide slot may be used for lettering fractions.

Slots are arranged in a predetermined axial relation to each other in order to effect proper axial positioning of the lettering characters of a note line. Again, using the narrow slot as the basic one facilitates the problem of properly laying out slots in the guide. The intermediate slot 14 is so arranged that its lower edge 14a is disposed along the line of the lower edge 15a of the narrow slot 15, the upper edge 14b of the slot 14 being thus caused to extend above the upper edge 15b of the slot 15. The radius of corners 16, i. e., places of juncture of edges 14b and 15b as well as 12b and 14b and 12a and 14a is made sufficiently small in order not to separate the slots unnecessarily. I prefer to make this radius approximately one half of the width of slot 15. By virtue of such a construction it becomes possible to write a capital letter through the right-hand end of the intermediate slot 14 and to follow it with a line letter written through the left-hand end of the narrow slot 15 without appreciably shifting the guide. (See Fig. 4.)

The wide slot 12, which in the present embodiment of the invention is arranged to the right of the intermediate slot 14, is so disposed as to have its center line substantially along the line drawn or struck against the upper edge 15b of the narrow slot 15 as a guiding edge. By virtue of such a construction the upper and the lower edges 12a and 12b thereof extend, respectively, above the upper and lower edges of the slots 14 and 15. This makes the slot 12 suitable for writing therethrough fractions which are thus placed in a proper axial relationship to the whole numbers written through the intermediate slot 15. (See Fig. 4.) In addition, when the wide slot is used for lettering therethrough large letters, such as used in title blocks, the center bars of the letters F, E, G, H, and dashes in general may also be written as short lines struck against 15b as a guiding edge (see Fig. 5), while for writing the cross bar of the letter A the lower edge 15a of the same slot 15 may be used. This eliminates much of the free-hand work in lettering. Also, dimension lines may be drawn against the edge 15b in the same operation as in drawing the fraction signs, while witness lines may be drawn

against the vertical edges or ends of the body 10. Thus, a number of dimension lines and dimensions may be placed on the drawing without shifting the guide transversely.

5 In operation, the guide is placed against a T-square or a triangle or any other device having a guiding edge, and is brought together with such device into a position where the slot 15 is properly located to letter the line of line letters 10 of the desired note. Vertical lines 20 are used for properly aligning the beginnings and the ends of note lines. Inclined lines 21 drawn at the angle of $67\frac{1}{2}$ degrees to the slots provide reference lines to insure proper inclination of letters if inclined stroke is used. It should be noted, however, that the provision of inclined lines does not prevent use of the device for vertical stroke lettering, in which case the lettering is done with reference to the vertical lines and disregarding the inclined lines. (See Fig. 4.)

25 The left-hand end of the wide slot 12 may be used for partly forming letters such as F, E, I, H, and the like, done with the use of inclined stroke. If, however, it is desired to have the same advantage for the vertical stroke lettering, the left-hand end of the slot 12 is finished vertically as shown in Fig. 7. It will be noted, however, that in this case the lettering guide can still be used just as conveniently for inclined 30 lettering.

35 Actual lettering is done through the slots as mentioned, and the guide is shifted to the right or left as required. If it is necessary to start with a capital, the same is written through the right-hand end of the intermediate slot 14, and the next line letter is written through the left-hand end of the narrow slot 15, as mentioned. (See Fig. 4.) Should it become necessary to write a figure, the guide is shifted to the right to bring the intermediate slot 14 to the place where the figure or figures are to be written. Should it become necessary to write a fraction, the fraction sign is first written or drawn against the upper edge 15b of the slot 15; thereupon the 40 guide is shifted to bring the wide slot 12 over the fraction sign, and the numerator and the denominator are written against the edges 12b and 12a respectively. Thus a fraction of a proper height disposed in a proper axial arrangement to the line letters or the figure is produced. When lettering in lower case, the letters such as l, h, d, and the like are written entirely or finished through the intermediate slot 14, while the wide slot 12 is similarly used for the 45 letters y and g. (See Fig. 6.)

50 It is important to note that the lengths of all slots, and particularly of the narrow slot 15, are such that a plurality of lettering characters can be written without shifting the device. 60 I prefer to make the narrow slot approximately three inches long, which permits writing several words composed of line letters without shifting the device. Thus, in my improved lettering guide, the lettering operation continues without shifting the guide until one comes to the end of the slot or the end of the line in a note, or until the next lettering character is of a different width than the one previously written. This 65 constitutes a great advantage over the "individual letter" guides which must be shifted at each lettering character. In average engineering lettering, where letters are small and speed is a primary consideration, as is the case in pencil lettering, such shifting makes drawing every lettering character against the edges of 70 75

its individual stencil opening highly objectionable. Moreover, in lettering through a stencil the pencil has to be held in a nearly vertical position, as in drawing, while with my improved guide it may be held in a normal writing position, which reduces muscular strain and fatigue on the draftsman's hand and arm, increases the speed of lettering, and in general is more convenient. In addition, having a number of slots of different widths, the user may letter notes in various sizes, and particularly use the wide and the intermediate slots for lettering in title blocks. This makes a single one of my improved lettering guides sufficient for lettering and dimensioning the entire drawing, either in vertical or inclined stroke, while the use of "individual letter" guides requires a special guide for each size of letters, and therefore a set of several guides must be available in order to complete a drawing, the entire set being limited to either vertical or inclined stroke letters.

Two distance-measuring lines 22, running parallel to all of the slots and located preferably above them, are provided. By placing one of said lines against the top or the bottom of a previously written line, the predetermined spacing for the next lower line is thus obtained. By providing two of the lines 22, the choice of four distances between the lines is made available.

The body 10 is chamfered at its upper surface around all of the slots are shown at 23, in order to facilitate lettering and to prevent too much clearance between the writing point and the edge of the slot on the surface of the paper, or in other words, to prevent the lettering characters from coming out smaller than desired with a given width of slot.

On the bottom surface, opposite the chamfer 23, the body 10 is provided with a small chamfer 24, which may be done by scraping, said chamfer 24 intended to prevent smearing of the lettering when working with ink.

Under certain conditions it may be desirable to provide only two slots on a guide or more than three slots. This, of course, does not change the general concept in accordance with which my improved lettering guide is constructed, since such slots are laid out in accordance with the procedure outlined above in order to provide the required respective widths and axial arrangement of the lettering characters.

It is preferable to provide all reference lines on the lower surface of the device, in order to avoid confusing shadows or distortion of view if material of convenient thickness is used, and the lines are provided on the upper surface of the device.

There is thus provided a simple and inexpensive lettering guide with the aid of which lettering on engineering drawings, which usually include line letters, capitals, figures, fractions, as well as large size letters for title blocks and the like, may be done with great rapidity and convenience and with greatly reduced eyestrain as well as muscular and nervous fatigue. Thus one of the important industrial operations, which consumes a great portion of the total working time of highly skilled help, is made more efficient, and great savings of time and money and a greater productiveness of engineering designing work is achieved.

I claim:

1. In a lettering guide, a body having a straight guiding edge, said body being provided with at

least two longitudinally adjacent slots having edges extending parallel to said guiding edge, the lower edges of said slots extending along the same straight line, one of said slots being narrower and having length sufficient to provide for lettering therethrough of more than one character without shifting the device.

2. In a lettering guide, a body having a straight guiding edge, said body being provided with at least two longitudinally merging slots having edges extending parallel to said guiding edge, the lower edges of said slots extending along the same straight line, the widths of said slots being selected to provide for lettering therethrough of capitals and line letters, respectively, the lengths of each of said slots being sufficient to provide for lettering therethrough of more than one character.

3. In a lettering guide, a body having a straight guiding edge for being shifted thereon, said body being provided with two longitudinally merging slots having edges extending parallel to said guiding edge, the lower edges of said slots extending along the same straight line, the widths of said slots being selected to provide for lettering therethrough of capitals and line letters, respectively, the lengths of each of said slots being sufficient to provide for lettering therethrough of more than one character, and a line provided on said body above said slots, and extending parallel to their common lower edge.

4. In a lettering guide, a body having a guiding edge, said body being provided with at least three longitudinally adjacent slots parallel to said edge, two of said slots having a continuous lower edge and their respective widths selected to provide for lettering therethrough capitals and line letters for such capitals, the upper and the lower edges of the third slot being disposed respectively above the tops and below the bottoms of said two slots substantially in a relationship to provide for lettering through said slot of fractions for the line of characters lettered through said two slots.

5. In a lettering guide, a body having a guiding edge, said body being provided with at least three longitudinally adjacent slots parallel to said edge, two of said slots having a continuous lower edge and their respective widths selected to provide for lettering therethrough of capitals and line letters for such capitals, the edges of the third slot being disposed in such a relationship respectively the tops and the bottoms of said two slots as to provide for lettering through said third slot of fractions for the line of characters lettered through said two slots, the center line of said third slot being disposed approximately along the line which is drawn against the upper edge of the slot for writing line letters.

6. A lettering guide comprising a body having a straight guiding edge, said body being provided with at least three longitudinally adjacent slot portions merging into each other and extending parallel to said edge in a predetermined axial relationship to each other to form a combination slot, the first slot portion having width to enable lettering therethrough line letters of a predetermined height; the second slot portion having its lower edge extending along the same straight line with the lower edge of said first slot portion and its upper edge extending above the upper edge of said first slot portion to a distance enabling lettering through said second slot portion capitals for the line characters lettered through said first slot portion; and the third slot portion

having its width and axial relationship to said first and second slot portions selected to provide for lettering through said third slot portion fractions for the characters lettered through said first and second slot portions.

7. In a lettering guide, a body having a straight guiding edge, said body being provided with at least two longitudinally arranged slots parallel to said edge, one of said slots being wider and having its edges disposed respectively above and below the top and the bottom edges of the narrower slot to provide for lettering through said wider slot of fractions corresponding in size to the size of lettering characters to be lettered through said narrow slot, said narrow slot having length sufficient to letter therethrough a plurality of characters without shifting the guide.

8. In a lettering guide, a body having a straight edge, said body being provided with a plurality of longitudinally adjacent lettering slots of different widths arranged parallel to said straight edge, at least one of said slots having length suf-

ficient to letter therethrough a plurality of lettering characters without shifting the guide, the respective widths and the axial relationship of said slots having the same relationship as the heights and the axial positioning of lettering characters of at least one predetermined font thereof.

9. In a lettering guide, a body having a straight edge, said body being provided with a combination slot extending along said straight edge and having its longitudinal edges parallel thereto, said combination slot being composed of a plurality of longitudinally adjacent slot portions merging into one another at their adjacent ends, at least one of said slot portions having length sufficient to letter therethrough a plurality of lettering characters without shifting the guide, said slot portions having different but mutually correlated widths and a correlated axial arrangement corresponding to those of lettering characters of at least one predetermined font thereof.

GREGORY S. DOLGORUKOV.
